UNITED STATES PATENT OFFICE.

HENRY BREHMER, OF STAPLETON, ASSIGNOR TO DAVID WOLFE BRUCE, OF NEW YORK, N. Y.

DESIGN FOR TYPE.

SPECIFICATION forming part of Design No. 16,599, dated April 6, 1886.

Application filed March 4, 1886. Serial No. 194,071. Term of patent 14 years.

To all whom it may concern:

Be it known that I, HENRY BREHMER, (assignor to DAVID WOLFE BRUCE,) of Stapleton, Richmond county, New York, have invented 5 and produced a new and original Design for a Font of Printing-Type, of which the following is a specification.

The nature of my design is clearly shown in the accompanying typographic impression, to 10 which reference is made, and consists of an unshaded letter. The left-hand portion of the A, H, and J is curved to the left at its top, as shown. The M and N are ornamented by the curved lines at the upper right and left hand 15 terminations. In the B, D, P, and R the upper rounding portion forms, as it were, a continuation of the up and down portions, curving outward from the same. In the C, E, F, and G the inclined line with heavy dot termina- 20 tion is found at the upper right hand. In the H and K the heavy dot is found at the upper right hand. In the L the inclined line with heavy dot termination is found at the 25 base on the right, and this ornamentation characterizes both terminations of the S, T, and Z.

The character of the design is preserved in

the symbol &, the punctuation - marks, the numerals, and dollar and pound - sterling marks.
